UNITED STATES PATENT OFFICE.

EMIL IBACH, OF PHILADELPHIA, PENNSYLVANIA, ASSIGNOR, BY MESNE ASSIGNMENTS, TO BUDD WHEEL COMPANY, OF PHILADELPHIA, PENNSYLVANIA, A CORPORATION OF PENNSYLVANIA.

METAL WHEEL.

Application filed May 12, 1919. Serial No. 296,401.

To all whom it may concern:

Be it known that I, EMIL IBACH, residing at Philadelphia, in the county of Philadelphia and State of Pennsylvania, have invented certain new and useful Improvements in Metal Wheels, of which I declare the following to be a full, clear, and exact description.

This invention relates to metal wheels and the process of making the same, and particularly to the type of wheel which is made up of a plurality of metal discs suitably connected together.

One object of the invention is to provide a wheel of this character, which is of novel construction and provides a wheel structure, which is efficient, strong, durable, economical of manufacture, and easily assembled.

A further object of the invention is to provide a metal wheel made up of a plurality of sheet metal discs secured together in a novel manner, and provided with means for suitably supporting a wheel rim thereon.

A further object of the invention is to provide a new and improved process for manufacturing metal wheels.

Further objects of the invention relate to economies of manufacture and details of construction as will hereinafter appear from the detailed description to follow.

The objects of the invention are accomplished in one instance by the devices and means described in the following specification, but it is evident that the same may be varied widely without departing from the scope of the invention, as pointed out in the appended claims.

A structure constituting one embodiment of the invention, which may be the preferred, is illustrated in the accompanying drawings forming a part hereof, in which:

Figure I is a side elevational view of a metal wheel embodying the present invention.

Figure II is a fragmentary transverse, sectional view through the metal wheel, taken along the line II-II of Figure I, and illustrating the formation of the metal discs.

Figure III is a transverse, sectional view, taken along the line III-III of Figure I.

Figure IV is a transverse sectional view of a modified form of wheel structure, which is similar to Figure III, and discloses an ar-

angement of the various parts which may be employed in the construction of front wheels.

In the drawings, similar reference characters refer to corresponding parts throughout the several views and the sectional views are taken looking in the direction of the small arrows at the ends of the section lines.

In general, the invention comprises a pair of sheet metal discs, each of which is provided with radially extending portions offset outwardly from the plane of the disc, and which are adapted to register with each other for the purpose of forming what may be termed spoke portions, which are adapted to add to the strength and rigidity of the structure. Each of the discs is also provided with central openings surrounded by circular channels within which are positioned hub members, while the outer peripheral edges of the discs are provided with annular flanged portions co-operating with each other to form, when in assembled position, channels for the reception of angular brace members to which the outer edges of the flanged portion are secured and upon the outer surfaces of which, and the outer peripheral portions of the flanges, is secured a rim or felloe band of the usual construction.

In the embodiment of the invention illustrated herewith, an inner disc 10 and an outer disc 11 are constructed in a substantially similar manner, each of the discs being provided with a central opening formed therein, the inner peripheral edge of the disc 10 being bent inwardly at 12, as shown in Figure III. The disc 10 is provided with a substantially circular portion 13, surrounding the central opening formed therein, while, in a similar manner, the disc 11 is provided with a similar portion 14, which surrounds the central opening formed therein and registers with the portion 13 of the disc 10 when the discs are properly assembled in position relative to each other. The disc 10 is provided with a plurality of radially extending outwardly pressed spoke sections 15, which may be pressed out into the same plane as the circular portion 13. The disc 11 is provided in a similar manner with a plurality of radially extending outwardly pressed spoke sections 16 all formed in the disc 11, the spoke sections 15 and 16

of the two discs being adapted to register with each other, when the discs are properly assembled, in such a manner as to provide a plurality of outwardly pressed spoke sections extending throughout the circumference of the wheel.

The outer peripheral portion of the disc 10 is pressed outwardly at 17, in a direction substantially at right angles to the plane of 10 the main portion of the disc, and then radially at 18 in a direction substantially parallel with the plane of the disc, and from thence bent inwardly to form peripheral flanges 19, the bent portions 17, 18 and 15 19 being positioned in such a manner as to provide an annular channel portion 20. The disc 11 is formed in a similar manner to the disc 10 being bent outwardly at 21 and provided with a portion 22 substantially parallel 20 to the plane of the disc from which extends an inturned flange 23, the parts 21, 22 and 23 forming a channel 24 which is of similar construction to the channel 20, and is adapted to register therewith when the discs 25 10 and 11 are properly positioned with respect to each other. As the radially extending spoke sections 15 and 16 are pressed from the original planes of the discs, portions 25, upon the two discs, remain in the original 30 planes of the discs, and these portions are of similar form and adapted to register with each other when the discs are assembled in such a manner as to provide suitable means for securing the discs together by spot welding, as indicated at 25'.

Positioned within the annular recess formed by portions 13 and 14 of the discs 10 and 11, is a pressed metal ring 26, one edge of which is adapted to bear against 40 the interior surface of the plate 11, while an angular portion 26' thereof is formed in such a manner as to be parallel with and to bear against the interior surface of the disc 10. The ring 26 is provided with a rounded 45 portion 27 adapted to fit against the inturned rounded portion 12 of the plate 10, and a portion 28 extends therefrom and fits within the circular opening formed in the center of the disc 11. This ring 26 thus serves as a 50 spacing means for properly spacing the portions 13 and 14 of the discs 10 and 11 from each other, and the exterior circumferential surface of this plate is provided with a plurality of transverse channels 29 so positioned 55 as to partially surround openings 30 formed in the portions 13 and 14 of the plates 10 and 11 for the purpose of better supporting these portions of the plate with reference to securing bolts which pass through the registering openings 30 formed in the two discs. The plate 26 is firmly secured to the discs 10 and 11 by being spot welded thereto as indicated at 31.

A plurality of T-shaped brace members 33, 60 each of which is provided with a main web

portion 34 and a pair of transversely extending flanges 35 adapted to be positioned at substantially right angles with respect to the main web portion 34 are provided for insertion in the registering channels 20 and 24 70 formed in the peripheral portions of the discs 10 and 11. The flanged portions 35 of the T-shaped braces rest upon the outwardly extending portions 17 and 21 of the discs 10 and 11 respectively, and are firmly 75 secured thereto by being spot welded to those portions as indicated at 36. Each of the T-shaped brace members is provided with a portion 38 extending beyond the main web portion 34 thereof a sufficient distance 80 so that, when the braces are properly assembled in the channels 20 and 24, the portion 38 is positioned between the adjacent edges of the inturned flanges 19 and 23 and terminates flush with the exterior surface 85 of the flanged portions. A rim or felloe band 40 is positioned upon the outer surface of the peripheral flanges 19 and 23, and is shrunk thereon in such a manner as to bear 90 against the outer surfaces of these flanges 90 and the projecting portions 38 of the T-shaped braces 33.

In the modified form of wheel structure illustrated in Figure IV, the parts are constructed in a manner similar to those described above except that the out-turned portions 42 of the plate 10 are considerably shorter than the out-turned portions 41 of the plate 11, thus producing a construction wherein the plane 43 of the mating portions 100 of the discs 10 and 11 is offset from the central longitudinal plane of the wheel tread instead of being positioned substantially within the longitudinal center line of the wheel, as illustrated in the modification 105 shown in Figure III.

In the construction of the wheel shown in Figure III, the discs 10 and 11 are pressed into the form shown in the drawings and then assembled in position relative to each other with the ring 26 interposed therebetween, the discs 10 and 11 being positioned in such a manner relatively to each other that the radially extending outwardly pressed spoke sections 15 and 16 register 110 with each other, and the ring 26 being so arranged relatively to the discs 10 and 11 that the channels 29 formed therein properly register with the openings 30 formed in the discs 10 and 11. When assembled in this manner the mating sections 25 of the discs 10 and 11 are in registry and bear against each other and are then secured together by spot welding. The ring 26 being properly positioned relatively to the discs 10 and 11 115 is securely attached to the discs by being spot welded thereto as indicated above. The discs 10 and 11 being properly secured together in the manner described, the T-shaped braces are positioned within the peripheral 120

channels formed by the external flanges upon the discs and are rotated 90° so that the opposite end portions thereof lie within the registering channels 20 and 24 whereupon the flanged portions 35 of the T-shaped braces are secured to the outwardly extending portions 17 and 21 of the corresponding discs by being spot welded thereto. The tire 40 is then shrunk upon the outer peripheral 10 surface of the inturned flanges 19 and 23 and upon the portions 38 of the T-shaped braces which extend to such a point as to be substantially flush with the exterior of the inturned flanges 19 and 23.

15 From the above description it will be evident that a disc wheel of the structure described above is capable of being readily and easily produced, and provides a wheel structure of this type which is comparatively 20 light in weight, and which is particularly strong and durable and is capable of withstanding the various strains to which wheels of this character are ordinarily subjected.

While I have shown and described in considerable detail a specific embodiment of my invention, it is to be understood that this showing and description is illustrative only, and for the purpose of rendering my invention more clear, and that I do not regard the invention as limited to the details of construction illustrated or described, nor any of them, except in so far as I have included such limitation within the terms of the following claims, in which it is my intention to claim all novelty inherent in my invention broadly as well as specifically.

What I claim as new and desire to secure by Letters Patent is:

1. In a metal wheel, the combination of a pair of sheet metal discs provided with registering radial ribs and peripheral channels, the central portions of the disc being offset and spaced from each other, the portions of said discs between said ribs being secured together in contact with each other, a channel spacing ring positioned between said discs with the base of the channel contacting and integrally secured to the central portion of one of said discs, and a rim 40 mounted on the side walls of said peripheral channels.

2. In a metal wheel, a pair of sheet metal discs provided with registering radial ribs and registering peripheral channels, a spacing member formed of sheet metal and interposed between the metal discs at the hub and a plurality of T-shaped braces positioned within the peripheral channels of the discs.

3. In a metal wheel, a pair of sheet metal discs provided with registering radial ribs and cooperating contacting portions spot-welded together, a channel-shaped sheet metal spacing ring interposed at the hub between the sheet metal discs and disposed

with the base of the channel contacting with and secured to one of said discs, flanges formed upon the peripheral edges of the disc and a rim positioned upon said flanges.

4. In a metal wheel, a pair of sheet metal 70 discs provided with registering radial ribs and co-operating mating portions adapted to be spot welded together, flanges formed upon the peripheral edges of the discs to provide channels, braces positioned within 75 the channels thus formed, and a rim positioned upon the peripheral flanges and the outer portions of the braces.

5. In a metal wheel, a pair of sheet metal 80 discs provided with registering radial ribs and co-operating mating portions and having central openings formed therein, the said discs being spot welded together, flanges formed upon the peripheral edges of the discs in such a manner as to provide channels, transverse braces positioned within the channels, and a rim positioned upon the peripheral flanges and the outer portions of the braces.

6. A method of making metal wheels including the following steps: assembling a pair of sheet metal discs provided with peripheral flanges in such a manner that co-operating mating portions of the metal discs are in contact and registry, spot welding the sheet metal discs to each other, positioning brace members upon the peripheral flanges, and spot welding said braces to the peripheral flanges.

7. A method of making metal wheels including the following steps: assembling a pair of sheet metal discs provided with peripheral flanges in such a manner that co-operating mating portions of the metal discs are in contact and registry, spot welding the sheet metal discs to each other, positioning brace members upon the peripheral flanges, spot welding said braces to the peripheral flanges and mounting a rim upon the brace members.

8. In a wheel structure, the combination of a pair of metal discs, each having the central portion struck out of the plane of said discs and having a plurality of ribs struck out of the plane of the disc and extending radially from said central portion, the peripheral portions of said discs being struck out to form annular channels, said discs being assembled and connected together with the surfaces between said ribs in contact, reinforcing members seated transversely in said channels and a rim carried by the peripheries of said discs.

9. In a wheel structure, the combination of a pair of metal discs assembled and connected together with the surfaces of the major portions of said discs in contact, the peripheral portions of said discs being struck out to form annular channels, reinforcing members seated transversely in said chan-

nels and a rim carried by the peripheries of said discs.

10. In a wheel structure, the combination of a pair of metal discs, each having a central portion struck out of the plane of the disc and having a plurality of ribs extending radially from said central portion, said discs being assembled and connected together with the surfaces between said ribs in contact, a sheet metal channel-shaped spacing ring interposed between the central portions of said discs with the base of the channel contacting with and secured to one of said central portions, and a rim peripherally carried by said discs.

11. In a wheel structure, the combination of a pair of metal discs each having the central portion struck out of the plane of the disc and having a plurality of ribs extending radially from said central portion, said discs being assembled and connected together with the surfaces between said ribs in contact, a spacing ring of channel-shaped cross-section interposed between the central portions of said discs with the base of said ring against one of said discs, and a rim carried by the peripheries of said discs.

12. The method of making wheels including the following steps: forming a pair of wheel discs each with a central portion struck out of the plane of the disc, welding a spacing ring to the central portion of one

of said discs, welding the central portion of the other disc to said ring, welding said discs together with the surface of the major portions thereof in contact, mounting a rim on the peripheries of said discs.

13. The method of making metal wheels including the following steps: forming a pair of metal discs each having a central portion and radially extending ribs struck out of the plane of said disc, assembling a ring of channel-shaped cross-section with its base in contact with the central portion of the first disc, welding said base to said central portion, assembling the said discs with the surfaces of the discs between the ribs in contact with each other, welding the second disc to said ring, welding said mating surfaces together, and mounting a rim on the peripheries of said discs.

14. The method of making metal wheels including the following steps: forming a pair of metal discs each having its peripheral portion struck out to form an annular channel, connecting said discs together with the surfaces of their major portions in contact, positioning a plurality of transverse reinforcing pieces in said channels, welding said pieces thereto, mounting a rim on the peripheries of said discs.

In testimony whereof, I affix my signature.

EMIL IBACH.
